UNITED STATES PATENT OFFICE.

ARNOLD SESSLER, OF NEW YORK, N. Y.

DESIGN FOR A STOCKING.

SPECIFICATION forming part of Design No. 26,305, dated November 17, 1896.

Application filed April 24, 1896. Serial No. 588,976. Term of patent 14 years.

To all whom it may concern:

Be it known that I, ARNOLD SESSLER, a citizen of the United States, residing at New York city, in the county and State of New York, have invented and produced a new and original Design for Bicycle-Stockings; and I do hereby declare the following to be a full, clear, and exact description of the same, reference being had to the accompanying drawings, forming a part thereof.

The object of my invention is a stocking having the appearance to a greater or less degree of a legging such as is commonly worn by bicyclists.

In Figures 1 and 2 of the accompanying drawings I have shown a stocking-foot A, which is of any usual stocking material and which simulates a legging, comprising the legging portion B, so designed and arranged as that the portion C thereof will overlie the stocking-foot A, and hence when the stocking-foot is in the shoe the portion C will overlie the shoe and simulate closely the appearance of a legging at that point. To further carry out the design of a legging, a rib D is arranged along the line of the usual opening in leggings. This rib may be made from the material of the stocking itself or may be an addition thereto, its design being to simulate

the opening in the legging. Along the line 30 of this rib I provide buttonholes or a representation of them, (lettered E in the drawings, with buttons lettered F.) At the bottom of the legging I provide the strap G, which is secured to the legging in the usual way and 35 is intended to pass under the shoe of the wearer and be attached to a button on the opposite side in the well-known manner.

The leading feature of my design consists in a stocking-foot with an overlapping portion 40 forming the stocking-leg, which portion is provided with a rib having arranged adjacent thereto a series of buttons and buttonholes or imitation buttonholes, so that when the stocking is worn a portion thereof will 45 overlap the shoe after the manner of a legging, and the rib and buttons and buttonholes will further carry out the appearance of a legging.

What I claim is—

The design for a bicycle-stockings substantially as shown and described.

This specification signed and witnessed this 22d day of April, 1896.

ARNOLD SESSLER.
